The ornamental design for a removable computer storage module, as shown and described.

DESCRIPTION

FIG. 1 is a top front and right side perspective view of the removable computer storage module showing our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof;

FIG. 7 is a right side elevational view thereof; and,

FIG. 8 is a top, front, and right perspective view of the module of FIG. 1 as that module would appear when a user has raised its handle.
